UNITED STATES PATENT OFFICE.

HARRY ARTHUR BRAGG, OF SEATTLE, WASHINGTON.

DESIGN FOR A SOUVENIR BADGE.

No. 39,850.

Specification for Design.

Patented March 2, 1909.

Application filed October 25, 1906. Serial No. 340,608. Term of patent 7 years.

To all whom it may concern:

Be it known that I, HARRY ARTHUR BRAGG, a subject of the King of England, residing at 2126 Second avenue, west, city of Seattle, county of King, and State of Washington, have invented the new, original, and ornamental Design for a Souvenir Badge, of which the following is a specification, reference being had to the accompanying drawing, forming a part thereof, in which the figure is an elevation showing the design of the souvenir badge.

I claim—

The ornamental design for a souvenir badge as shown.

HARRY ARTHUR BRAGG.
